UNITED STATES PATENT OFFICE.

WILFRED I. OHMER AND JOHN E. McALLISTER, OF DAYTON, OHIO, ASSIGNORS TO THE RECORDING AND COMPUTING MACHINES COMPANY, OF DAYTON, OHIO, A CORPORATION OF OHIO.

INDICATOR.

1,169,424.

Specification of Letters Patent.

Patented Jan. 25, 1916.

Application filed July 25, 1912. Serial No. 711,431.

To all whom it may concern:

Be it known that we, WILFRED I. OHMER and JOHN E. McALLISTER, citizens of the United States, residing at Dayton, in the county of Montgomery and State of Ohio, have invented certain new and useful Improvements in Indicators, of which the following is a specification, reference being had therein to the accompanying drawing.

10 This invention relates to indicators and is designed more particularly for use as a fare indicator on street cars and the like.

One object of the invention is to provide an indicating device which will comprise 15 within itself an indicator, a register and a recorder and to this end we provide a device having three indicating mechanisms, one to indicate the class of the item received, a second to indicate the number of 20 items of all classes received during a stated period and a third to record and indicate the number of items of each class received during one or more such periods.

Another object of the invention is to provide 25 an indicator, for use in conjunction with a register, which will be actuated to indicate a particular item only when the register is operated to register that item; which will remain in a position to indicate 30 the item last registered until another and different item has been registered; and which will exhibit the same indication on both sides thereof.

Another object of the invention is to provide 35 an indicator which can be used in conjunction with a register, or other device employed in connection with the collection of fares or other items, or by itself; which will indicate the number of items, of all 40 kinds received; and which will exhibit this indication on both sides of the indicator.

To this end it is also an object of the invention to provide a double counting-indicator which will exhibit the same item on 45 both sides thereof.

Another object of the invention is to provide 50 in conjunction with a register an indicator which will be actuated upon each operation of the register to cause it to indicate the character of the item registered, and to compute the total number of items registered; and which will also be actuated to reset the computing mechanism to zero when the register is reset to zero.

55 A further object of the invention is to

provide an indicator which will exhibit a classified record of the items received.

In the accompanying drawings, Figure 1 is a front elevation of a mechanism embodying our invention, showing the register partially in section; Fig. 2 is a vertical, sectional view taken through the indicator; Fig. 3 is a detail view of the transfer mechanism for the classified indicator; Fig. 4 is a section showing in detail the resetting device for the total item indicator; Fig. 5 is a front elevation of the indicator with the casing broken away to show the indicating mechanism; Fig. 6 is a horizontal section taken on the line *z z* of Fig. 5 and looking 60 in the direction of the arrows; Fig. 7 is a section taken on the line *y y* of Fig. 5 and looking in the direction of the arrows; Fig. 8 is a detail view of the item indicator and its operating devices; Fig. 9 is a detail view 65 of the operating rod showing its connection with the indicator; Fig. 10 is a detail view of the hand operated resetting device for the counting-indicator; Fig. 11 is a detail view 70 of the locking device for the counting-indicator; Fig. 12 is a detail view of the arrester for the operating rod; Fig. 13 is a horizontal section taken through the indicator casing immediately above the classified indicating device and showing the latter and its operating mechanism in plan; Fig. 14 is a detail view of a portion of the 75 operating yoke for the classified indicating device; Fig. 15 is a detail view of the cam block carried by the operating rod; Fig. 16 is a transverse section taken through the classified indicating device showing one of the actuating pawls; Figs. 17, 18 and 19 are detail views showing the relative positions of the actuating pawls for the classified 80 record; Fig. 20 is a perspective view of the operating mechanism for the double indicating register; Fig. 21 is a detail view of the bell ringing device; and Fig. 22 is a top, plan view of the mechanism showing 85 the relative positions of the operating and connecting rods.

In these drawings we have illustrated one embodiment of our invention and have shown the same in conjunction with a fare 105 register, or recorder, of a well known construction. This register comprises a frame 1 in which the registering mechanism is mounted. This registering mechanism is provided with suitable setting devices com- 110

prising a rotary setting shaft 2 connected by suitable motion transmitting devices 3 with a vertical setting rod 4 mounted on the car and provided with an actuating handle 5. 5 The registering mechanism further comprises operating devices, to cause the fare to be registered, including a slide bar 6 extending beyond the register and connected by suitable motion transmitting devices 7 10 with a vertical reciprocating operating rod 8 mounted adjacent to the setting rod 4 and provided with a suitable actuating device, such as a foot lever 9. The register itself has mounted therein an indicator 10 operatively connected with the moving parts thereof and the detail registering devices are adapted to be reset to zero at the ends of certain predetermined periods as, for example, the end of a trip in the case of a street car 15 fare register. This register is shown and described in Patent No. 990,666, granted to Ohmer, Whistler and McAllister and the setting and operating rods and the devices for connecting the same with the register are 20 shown in the Patent No. 1000,542, granted to Ohmer, Whistler and McAllister for register operating mechanism, and need not be here shown or described in detail. Such a register, when used for a fare register, for 25 example, is usually mounted in the upper part of the car, often near the top of the partition dividing the body of the car from the vestibule and it is, therefore, desirable that indicating mechanism should be provided which will be more nearly on the level 30 with the eyes of the passengers in the car. For this reason we have provided the present indicating devices and have shown the same as comprising an indicator which is 35 shown as a whole by the reference numeral 40 11 which is applied to the casing inclosing the indicating devices. The indicator is supported independently of the register, that is, it bears no fixed relation thereto but may 45 be mounted in such a position relatively to or at such a distance from the register as may be desirable. It will further be understood, however, that while we have shown and will now proceed to describe the indicator 50 as used in conjunction with a register many of its features may be utilized in an indicator alone without combining them with a register.

The present indicator comprises three sets 55 of indicating devices, one of which indicates the character of the item which has been registered, that is, in the case of a fare indicator, the class of the fare. The indicator may be adapted to handle any suitable number 60 of fares and these may be of any desired class. The present indicator is designed to take care of tickets, 8¢ cash fares, transfers and 5¢ cash fares. The second indicating device is for the purpose of registering and 65 indicating the number of items of all classes

which are received during a given period and which, in a fare indicator registers and indicates the number of fares received or the total number of passengers carried during a single trip. The third indicating device is a classified item indicator, which records the total number of items of each class received, and, in a fare indicator, shows the number of fares of each class which have been received during one or more trips. All 70 or a part of these indicating devices may be readable on both sides of the indicator. Thus, by mounting the indicator near the dividing line between the car and the vestibule or between any other two parts of the 75 car the indications will be visible on the platform. To take care of these three indicating devices the casing 11 has been provided with an enlarged lower portion to receive the counting-indicators which indicate the 80 total number of items of all kinds received and this enlarged portion is provided at each side with a sight opening 12, the two sight openings being offset one from the other but having their inner ends overlapping for 85 a purpose which will hereinafter appear. The upper portion of the casing 11 is contracted and that portion immediately above the enlarged portion which is adapted to contain the indicating devices to indicate the 90 class of the item registered also has two sight openings, 13, arranged on opposite sides thereof. The classified item indicator is mounted in the upper part of the casing 95 which is provided with a sight opening, 14, 100 in one side thereof.

Referring first to the indicating device for indicating the class or character of the particular item received it will be noted that this device comprises a plurality of independently movable indicating members which, in the present instance, are in the form of elongated plates or blades 15, each having on its two faces the name or symbol of some particular item, these 110 items being shown, in the present machine, as the several classes of fares above enumerated. These indicator blades are so mounted that they rest normally in substantially parallel positions below 115 the level of the sight openings and when all of them are in this position no indication will be visible through either opening. Means are provided for selecting and elevating into alignment with the sight 120 openings that blade bearing the indication corresponding to the item or fare which the register is operated to register. Further, this mechanism is such that the blade cannot be elevated until the register is actually 125 operated when it will be automatically raised into its indicating position and it will then remain in this position until the register has been again operated to register another fare of a different class, thus elimi- 130

nating all possibility of the indicator being tampered with or so manipulated as to indicate one fare when another fare has been registered. These results may be secured in 5 various ways but that herein illustrated is a practical and inexpensive one. In this form of the device the several blades are each supported by a pair of links 16, the links of each pair being pivotally connected 10 at one end to their blade and at their other ends to the casing or some other suitable supporting structure. Such a supporting device permits the blade to move vertically but holds it always in a horizontal position. 15 The operating rod 8, by means of which the register is operated to register each item, is provided with means for engaging one of the links 16 and elevating the indicator blade to which that link is attached. Setting devices are provided to enable this 20 means to be adjusted to cause the desired indicator blade to be elevated. To this end the elevating means is shown in the present instance as comprising a pin or projection 25 17 carried by a plate 18 rotatably mounted on the operating rod 8 between two collars 19. Rigidly secured to the plate 18 and rotatable therewith is a gear 20 which meshes with an intermediate gear 21, which gear is 30 preferably elongated, as shown in Fig. 5, to enable the gear 20 to have vertical movement relatively thereto without moving out of mesh therewith. The intermediate gear 21 meshes with a gear 22 rigidly secured to and 35 rotatable with the setting shaft 4. Consequently, when the shaft 4 is rotated to set the register for a particular fare the plate 18 carrying the pin 17 will also be rotated and the pin 17 brought into alinement with 40 the lower link of that particular indicating blade which bears the indication corresponding to the fare for which the register has been set. The operation of the operating rod 8, to cause the operation of the register 45 to register the particular fare for which it is set, causes the pin to engage the link of this blade and elevate the blade into its visible position. A suitable detent is provided to retain the indicator blade in its elevated 50 position and this detent is here shown as a spring-pressed dog 23 having a nose adapted to engage a pin 24 carried by the upper link. This dog is mounted on the shaft 25 and is held normally in an operative position by 55 means of a spring 26 engaging a projection 27 secured to the hub of the dog. A finger 28 projects from the opposite side of the hub and engages a fixed part of the mechanism to limit the forward movement of the 60 nose when the particular indicator blade is in its lowermost position. Connected with the operating rod 8 is a suitable tripping device, such as a collar 29, which will engage the projection 27 as the rod nears the upper 65 limit of its movement and move the nose of the dog 23 out of engagement with the pin 24, thus leaving the indicator blade free to move downward. The construction is such that in case the same fare is registered twice in succession the indicator blade will 70 not move into its non-indicating position. This is accomplished by so arranging the parts that when the operating rod is at the upper limit of its movement the pin 24 of the link will be some distance above the nose 75 on the dog 23 and as the rod moves downward to permit the indicator blade to move downward the dog will be released and will move into its operative position and thus again engage the pin 24 and retain the 80 blade in its indicating position.

In the present arrangement of parts the lower links occupy such positions that they would normally interfere with the movement of the pin 17 when the latter is in its 85 lowermost or normal position. To avoid this they have been provided with notches 30 arranged to permit the passage of the pin. Means have also been provided to prevent the movement of the pin 17 about the 90 axis of the operating rod during the operating movement thereof. This means, in one form, comprises a plate 31 rigidly secured to the plate 18, and is here shown as forming an extension of that plate, and having in its periphery a series of recesses 32, one of which will be moved into alinement with a projection or rib 33 carried by a fixed part of the frame when the pin is in 95 operative relation to one of the indicator 100 blades. When the operating shaft is moved upward the rib will enter the corresponding notch or recess in the plate 31 and will remain therein until the operating rod has practically completed its reciprocation, thus 105 retaining the operating rod 8 against rotary movement during its reciprocatory movement.

To prevent the operator from giving a short stroke to the operating rod and permitting it to return to its normal position without moving upward a distance sufficient to shift the indicating blades the rod is preferably provided with an arrester which is here shown as of a well known 115 type comprising a rack 34, rigidly secured to the rod, and a spring-held pawl 35^a adapted to ride over the rack in opposite directions during the two movements of the rod, thus making it necessary for the rod to 120 complete its movement in one direction before it can be moved in the opposite direction.

The indicating device for indicating the total number of transactions had, or in 125 the present instance, the total number of fares received, is here shown as consisting of a double group of indicating counter wheels, that is, counter wheels provided on their peripheries with figures or letters of 130

the proper size to enable them to be read at the desired distance. As here shown this group of counter wheels comprises five wheels, the two counter wheels at each end being visible only through the respective sight openings while the middle counter wheel is visible through both sight openings. As read from one side of the indicator the counter wheels 35 and 36 at the extreme left hand end of the group, as shown in the drawings, constitute the units and tens counters for one side of the indicator and the counter wheels 37 and 38 at the right hand end of the group constitute the units and tens counters for the opposite side of the indicator. Each of these counter wheels is provided with the numerals 0 to 9. The middle counter wheel 39, which is visible through both sight openings, constitutes the hundreds counter wheel for both sides of the indicator, and, to this end, is provided with two series of numerals running from 0 to 4 only. The several counter wheels all move in the same direction in the normal operation of the device and the corresponding counter wheels at the opposite ends of the group are moved in unison. Consequently, the same indication will be visible through both sight openings.

30 The mechanism for actuating the counters and transferring the count from one to the other may be of any suitable character, and is here shown as comprising a pawl and ratchet mechanism. Each counter wheel has secured to one side thereof a ratchet wheel 40 adapted to be engaged by one of a series of pawls 46, 47, 48 mounted upon a frame or yoke 41 which is journaled on the counter shaft 42, and is actuated by the operation of 40 the operating rod 8. The two ratchet wheels 40, which are secured to the units counter wheels 35 and 37, are each provided at a point immediately preceding the tooth which is engaged by the pawl to move the 45 zero indication of the respective counter wheels into view, with a recess 43 of a depth materially greater than the depth of the spaces between the other teeth of the ratchet. The ratchet wheels secured to the tens counters 36 and 38 are provided with recesses similarly located and of the same depth as the spaces between the corresponding teeth of the other ratchet wheels. The ratchet wheel carried by the hundreds counter 39 55 has the spaces between its teeth all of equal depth. The supporting frame or yoke 41 has journaled therein a shaft 45 on which are rigidly mounted five pawls arranged in alinement with the respective ratchet wheels 40. The two end pawls 46, which are adapted to actuate the units counters, are so positioned that they will normally engage their ratchet wheels when movement is imparted to the frame 41. The pawls 47 for 65 the tens counters occupy such positions rela-

tively to the pawls 46 that they will normally be held out of engagement with their respective ratchet wheels, while the pawl 48 for the hundreds counter occupies such position relatively to the pawls 47 that it will normally be held out of engagement with its ratchet wheel.

In the operation of the indicator when the units counters have been advanced nine spaces the pawls 46 will be brought into alinement with the deep spaces 43, thus allowing the pawls 46 to move downward a greater distance than usual and thus permitting the pawls 47 to operatively engage the teeth of their ratchet wheels, whereby the next operation of the pawl supporting frame 41 will cause both the units counters and the tens counters to be advanced one space. The pawl for the hundreds counter is, however, still held in an inoperative position because it is spaced farther away from its ratchet wheel than are the pawls for the tens counters. When the counters have been actuated to indicate 99 the pawls 46 and 47 will all enter their respective recesses 43 and 44, thus permitting the pawl 48 for the hundreds counter to engage its ratchet wheel, whereby the further operation of the pawl will cause all the counter wheels to be advanced one unit. A spring 49 tends to rotate the shaft 45 forwardly to move the pawls into engagement with the respective ratchet wheels. Operating movement may be imparted to the pawl supporting frame 41 in any suitable manner. Preferably, as above stated, this frame is actuated from the operating rod 8 and to this end the frame is provided with an arm 50 having a pin 51 extending laterally therefrom into a slotted arm 52 which is rigidly secured to the operating rod 8. Thus, the reciprocation of the rod 8 will impart a rocking movement to the frame 41 which will actuate those counters, the pawls of which are in operative relation thereto. Spring-pressed detent pawls 77 prevent the backward movement of the ratchet wheels during the return portion of the movement of the actuating pawls.

A suitable signal is sounded upon each operation of the operating rod 8 and in the present instance this signal comprises a bell 53 mounted in the lower part of the casing. A hammer 54 is pivotally mounted within the casing and connected with a pawl 55 having its nose held normally in engagement with the teeth of a ratchet wheel 56 on the shaft 42 by means of a spring 57. This ratchet wheel is loosely mounted on the shaft and is actuated by means of a pawl 58 carried by the pawl supporting frame 41 and having a hook-shaped nose which engages over the teeth of the ratchet wheel. By means of this construction the return portion of each operating movement of the frame 41 will cause the ratchet wheel 56 to be moved

one space, thus moving the pawl 55 outward against the tension of the spring 57 and permitting its quick return as it passes the end of the tooth, thus causing the hammer 54 to engage and ring the bell 53. It will be noted that the spring 57 serves to hold both the pawl 55 and the pawl 58 in engagement with the ratchet wheel 56. By means of this arrangement we not only utilize a single 10 spring for both pawls but the arrangement is such that the greatest tension will be upon the bell ringing pawl immediately prior to its release, thus utilizing the greatest strength of the spring to ring the bell.

15 The indicating counters are preferably utilized to indicate the number of detail transactions had within a given period, as the number of fares received during a single trip of the car. They are, therefore, adapted 20 to be reset at the end of such period and to this end the shaft 42 is a resetting shaft and is rotatably mounted. The shaft 42 is provided with a longitudinal groove 59 and each counter has pivotally mounted thereon 25 a spring-pressed dog 60 adapted to enter the groove 59 when brought into alignment therewith. The nose of the dog is so shaped that when the counter is rotated forwardly it will move out of the groove but when the 30 shaft is rotated in the direction of rotation of the counters the edge of the groove will engage the dog and cause the counter to rotate with the shaft. Consequently, during the normal operation of the counters the dog 35 will ride over the periphery of the shaft and when it is desired to reset the counters to zero the shaft is rotated and during its rotation will pick up the counters in whatever positions they may be and move the same to 40 zero. This resetting movement of the shaft may be secured in any manner and when the device is used in conjunction with a register it is preferably controlled by the resetting movement of the detail counters of the register. To this end the shaft 42 is shown in 45 Figs. 1, 2, 5 and 7 of the drawings as provided with a bevel gear 61 meshing with a similar gear 62 on the lower end of a shaft 63 which extends upward and is connected 50 by similar bevel gearing 64 with the resetting shaft of the detail counters of the register. Consequently, when those counters are 55 reset to zero the resetting shaft 42 of the indicating counters will be rotated to reset these counters to zero and the devices for controlling the resetting of the register counters will also control the resetting of the indicator counters.

When the indicator is used without a register it may be provided with any suitable means for enabling the indicating counters to be reset to zero and in Figs. 10 and 11 I have shown the shaft as provided with a hand wheel 65 instead of the bevel gear 61. 60 We have also shown the shaft as having

70 mounted thereon two cam disks 66 and 67. The disk 66 is rigidly secured to the shaft 42 and has a locking recess 68 adapted to receive the inturned nose 69 of an arm 70 pivotally mounted adjacent to the disk. A 75 spring 71 tends to hold the nose 69 normally within the locking recess of the disk and thus lock the shaft against rotation. When it is desired to reset the counters the arm 70 must be actuated to release the disk 66 and to this end a thumb lever 72 is connected therewith. The disk 67 is secured to the yoke or pawl-supporting frame 41, which is also mounted on the shaft 42. This disk is provided with a locking shoulder 73 and an 80 arm 74 is secured to the arm 70 and provided with a lip 75 adapted to be moved into the path of the shoulder of the disk 67 when the nose of the arm 70 is moved out of the locking recess in the arm 66, thereby 85 locking the pawl-supporting frame against movement during the resetting of the counters. The disk 66 is circular and consequently the nose of the arm 70 will ride on its periphery throughout the resetting movement of the shaft and will thus retain the lip of the arm 74 in locking position throughout that movement. Preferably, the disk 66 is 90 cut away on one side of the recess 68, as shown at 76, to permit the nose of the arm 95 to move inward and engage the opposite edge of the recess, thereby effectually preventing the overthrow of the resetting shaft. The cam disk 67 is segmental in shape and during the operation of the yoke to actuate 100 the counters this segmental portion of the disk will lie in the path of the lip 75 of the arm 74 and will thereby prevent the manipulation of the arms to release the resetting shaft. An arm 78 is rigidly connected with 105 the arm 70 preferably by securing the same to the shaft 108 on which the arm is mounted and is provided with a hook-shaped end portion arranged to engage a stud 79 mounted on the arm 50 to lock the same against 110 movement during the resetting movement of the shaft.

The indicator for classified items, which is mounted in the upper part of the casing, 115 comprises a shaft 80 on which are mounted several groups of indicating counter wheels, there being a group of these wheels for each class of transactions which the device is adapted to indicate. The left hand group of counters, indicated at 81, are, in the present arrangement of the machine, arranged to count and indicate tickets. The second group, 82, indicates the 8¢ cash fares, the third group, 83, indicates the transfers and the fourth group, 84, indicates the 5¢ cash fares. The units counters of the respective groups are actuated each time the other indicating devices are actuated to indicate the item, or fare, which that particular group of counters is designed to indicate. To this 120 125 130

end suitable selector mechanism is provided and controlled from the setting rod 4 to cause the operation of the units counter for the proper group. In the present form of the device each units counter has secured thereto a ratchet wheel 85 adapted to be engaged by a pawl 86 mounted on a pawl supporting frame 87 journaled on the shaft 80 and adapted to have operating movement imparted thereto by the movement of the operating rod 8. Mounted upon the shaft 80 adjacent to each of the ratchet wheels 85 is a disk 88 of a diameter slightly greater than the diameter of the ratchet wheel and having a cut-away portion or recess 89. The several disks are secured to the shaft 80 in such positions that the recesses 89 of the respective disks occupy different positions relative to the shaft. The pawls 86 are mounted in longitudinal alinement upon a rod 90 carried by the frame 87, are of the same length and have their noses of such a width that they extend across the periphery of both the disk and the ratchet. Obviously, so long as one of the pawls is in engagement with the periphery of its disk the movement of the frame 87 will not affect the ratchet wheel, and, inasmuch as the recesses of the several disks occupy different relative positions on the shaft only one pawl at a time can be in operative relation with its ratchet wheel and therefore the operation of the pawl supporting frame will impart movement to but one counter. The selection of this counter, as above stated, is controlled by the setting rod 4. For this purpose the shaft 80 has mounted on one end thereof a gear 91 meshing with one face of a double-faced rack 92, the other face of which meshes with an intermediate gear 93 which is rigidly secured to a second gear 94 which, in turn, meshes with a gear 95 secured to and rotating with the setting shaft 4. The ratio of the gears is such that the rack will be moved a distance sufficient to bring the recess of the disk 88 of the proper counter into such a position as to permit the operating pawl to engage said counter.

Operating movement may be imparted to the frame 87 and pawls 86 by means of the operating rod 8, and, to this end, the frame 87 is provided at that end adjacent the operating rod with a pin or projection 96 adapted to enter a cam slot 97 in a block 98 rigidly secured to the rod 8. The shape of the cam slot is such that the reciprocating movement of the rod 8 will rock the frame 7 and impart actuating movement to the pawls. If desired, the reciprocating block 98 may be mounted in a guideway 99 to hold the same more firmly in engagement with its pin. Spring-pressed pawls 100 engage the respective ratchet wheels to prevent their movement during the return movement of

the actuating pawls. The count may be transferred from the units counter to the tens counter and succeeding counters of each group in any suitable manner. In the present instance we employ the Geneva transfer mechanism, such as shown in Fig. 3 of the drawings, comprising a recessed disk 101 secured to the units counter and a pin 102 secured to that counter adjacent to the disk and adapted to engage a six toothed gear 103 once for each revolution of the counter wheel, thus advancing the gear 103 one step, this count being then transmitted to the tens counter through the usual gearing. This mechanism is well known and it is not thought necessary to describe the same in detail.

The fare register 1 includes recording devices, a part of which are indicated at 104 and which include all the items or fares recorded by the classified indicator 14. The register further includes printing mechanism for taking a record from these recording devices, this mechanism being here shown as comprising a platen 105 mounted in a movable carriage comprising a rack 106 adapted to be actuated by a gear 107. This mechanism is not shown or described in detail in the present application as it forms no part thereof and is fully shown and described in Patent No. 990,666, above mentioned. In this manner it will be noted that we have not only provided in an indicating device means for indicating the class of the fares received, other means for indicating the number of fares of all classes received during a given period, as during a trip of the street car, and a third means for recording and indicating the total number of items of each class received during a plurality of such periods or trips, but we have provided in connection with this device means for printing a removable record of the record indicated by the last-mentioned indicating means. While this printing means is here shown as a part of the register it will be obvious that this is not essential and that any suitable means may be provided for printing this record.

The operation of the mechanism will be readily understood from the foregoing description and it will be apparent that we have provided an indicator capable of use either alone or in conjunction with a register or other device employed in a similar relation; that this indicator will be actuated to indicate the character of the item which has been received only after the register has been operated to register that item, when the device is used in conjunction with a register, and will be locked in this position until another and different item has been received and registered, thus preventing the manipulation of the device to indi-

cate one fare and register another. Further, it will be apparent that we have provided means for indicating the total number of transactions had and that these indications 5 are visible from both sides of the indicator. Further, we have provided a classified indication of the different transactions had; and that the whole device is simple in construction, positive in its operation and of 10 such a character that it will not readily be disarranged or broken.

While we have shown and described one embodiment of our invention, in which it is coupled with a fare register, it will be understood that this has been chosen for the purpose of illustration only and that we do not desire to be limited either to the details of construction shown and described, for obvious modifications will occur to one 20 skilled in the art, or to the use of the invention in conjunction with a register or recorder, for it is obvious that it can be used alone or in conjunction with various other devices, such, for example, as a fare box.

25 Having thus fully described our invention, what we claim as new and desire to secure by Letters Patent, is:—

1. In an indicator, a casing having an opening, a plurality of indicating members 30 mounted within said casing and supported normally out of alinement with said opening, each of said indicating members being movable independently of the other indicating members, of a reciprocatory operating rod, an operating device carried by said operating rod and having reciprocatory movement therewith to move one of said indicating members into alinement with said opening, said operating device being 35 movable about the axis of said rod to enable it to be brought into operative relation with any one of said indicating members.

2. In an indicator, a casing having an opening, a plurality of indicating members 45 mounted within said casing and supported normally out of alinement with said opening, each of said indicating members being movable independently of the other indicating members, a vertically movable operating rod, an actuating device carried 50 by said rod and having vertical movement in unison therewith, said operating device being movable relatively to said rod to bring the same into operative relation with any one of said indicating members.

3. In an indicator, a casing having an opening, a plurality of indicating members mounted within said casing and supported normally out of alinement with said opening, each of said indicating members being movable independently of the other indicating members, an operating rod, an operating member mounted on said operating rod and having vertical movement therewith

and having movement about the axis of 65 said rod to bring the same into operative relation with any one of said indicating members.

4. In an indicator, a casing having an opening, a plurality of indicating members 70 mounted within said casing and supported normally out of alinement with said opening, each of said indicating members being movable independently of the other indicating members, an 75 operating rod, an operating member mounted on said operating rod and having vertical movement therewith and having movement about the axis of said rod to bring the same into operative relation with 80 any one of said indicating members, and setting mechanism to move said operating device relatively to said operating rod.

5. In an indicator, a casing having an opening, a plurality of indicating members 85 mounted in said casing and supported normally out of alinement with said opening, each of said indicating members being movable independently of the other indicating member or members, supporting devices connecting the respective indicating members with a fixed support and arranged to support said indicating members at all times in substantial horizontal positions, and means to actuate a selected one of said 90 indicating members to move it into alinement with said opening.

6. In an indicator, a casing having an opening, a plurality of indicating members mounted in said casing, a plurality of pairs 100 of links connecting the respective indicating members with a fixed support and arranged to support said members normally side by side and out of alinement with said opening, operating means to move a selected one of 105 said indicating members into alinement with said opening, and means to retain said member in alinement with said opening and arranged to be actuated by the movement of another indicating member 110 into alinement with said opening to release the first-mentioned member.

7. In an indicator, a casing having an opening, a plurality of indicating members mounted in said casing, a plurality of pairs 115 of links connecting the respective indicating members with a fixed support and arranged to support said members normally side by side and out of alinement with said opening, an operating member adapted to 120 be moved into operative relation with any one of said indicating members, means to actuate said operating member to cause it to move that indicating member with which it is in operative relation into alinement 125 with said opening.

8. The combination, with a register, a rotatable setting rod therefor, and a recip-

recable operating rod therefor, of an indicator separate from said register and comprising a plurality of indicating blades each capable of vertical movement independently of the other blades, an actuating member rotatably mounted on said operating rod and having vertical movement therewith, and means actuated by said setting rod to move said operating member into operative relation with one of said indicating blades.

9. The combination, with a register, a rotatable setting rod therefor, and a reciprocable operating rod therefor, of an indicator comprising a supporting frame, a plurality of indicating blades, a plurality of pairs of links connecting the respective blades with said frame to permit each blade to have movement relatively to the other blades, an operating member rotatably mounted on said operating rod and adapted to be moved into and out of alinement with the lower links of any one of the several pair of links, and an operative connection between said operating member and said setting rod.

10. The combination, with a register, a rotatable setting rod therefor, and a reciprocable operating rod therefor, of an indicator comprising a supporting frame, a plurality of indicating blades, a plurality of pairs of links connecting the respective blades with said frame to permit each blade to have movement relatively to the other blades, an operating member rotatably mounted on said operating rod and adapted to be moved into and out of alinement with the lower links of the several blades, a gear connecting said operating member, an elongated intermediate gear meshing with the first-mentioned gear, and a gear mounted on and rotatable with said setting rod and meshing with said intermediate gear.

11. The combination, with a register, a rotatable setting rod therefor, and a reciprocable operating rod therefor, of an indicator comprising a supporting frame, a plurality of indicating blades, a plurality of pairs of links connecting the respective blades with said frame to permit each blade to have movement relatively to the other blades, an operating member rotatably mounted on said operating rod and adapted to be moved into and out of alinement with the lower links of the several blades, an operative connection between said operating member and said setting rod, said operating member having a laterally extending portion provided in its edge with a series of recesses, and a rib carried by a fixed part of said indicator and adapted to enter one of said recesses when vertical movement is imparted to said operating member.

12. An indicator comprising a supporting frame, a plurality of indicating members

movably mounted on said frame and each having movement relatively to the others, a longitudinally movable operating rod, an operating member mounted on said rod and movable relatively thereto to bring the same into operative relation with any one of said indicating members, a plate connected to and movable with said operating member and having a series of notches therein, and a fixed part arranged to enter one of said recesses when longitudinal movement is imparted to said operating rod.

13. In an indicator, a casing having a sight opening in each side thereof, a plurality of indicating counter wheels mounted within said casing, a part of said counter wheels being arranged to be read through one of said sight openings, another part of said counter wheels being arranged to be read through another of said sight openings and still another part of said counter wheels being arranged to be read through both of said sight openings, actuating devices for said counter wheels, and means for operating said actuating devices.

14. In an indicator, a casing having a sight opening in each side thereof, a plurality of indicating counter wheels mounted within said casing, a part of said counter wheels being arranged to be read through one of said sight openings, another part of said counter wheels being arranged to be read through another of said sight openings and still another part of said counter wheels being arranged to be read through both of said sight openings, a ratchet wheel secured to each of said counter wheels, a yoke pivotally mounted on the axis of said counter wheels, a series of pawls carried by said yoke and adapted to engage the respective ratchet wheels, means for holding a portion of said pawls normally out of operative relation with their ratchet wheels, an operating rod, and a connection between said operating rod and said yoke.

15. In an indicator, a plurality of indicating counter wheels rotatable about a common axis, one of said counter wheels being readable from both sides of said indicator, the counter wheels on one side of the first-mentioned counter wheel being readable from one side only of said indicator and the counter wheels on the opposite side of said first-mentioned counter wheel being readable from the other side only of said indicator, and means for actuating said counter wheels.

16. The combination, with a register, and an operating device therefor, of an indicator separate from said register and comprising a series of indicating counter wheels arranged to exhibit the count on both sides of said indicator, and a connection between said indicating wheels and said operating device to cause a unit to be added to the in-

- dicating wheels upon each operation of the operating device for said register.
17. The combination, with a register, and a reciprocal operating rod therefor, of an indicator comprising an uneven number of indicating counter wheels, the middle counter wheel having two series of indications arranged in a single row about the periphery thereof to exhibit the same indication simultaneously on both sides of said indicator, the counter wheels on one side of said middle counter wheel being readable on one side of said indicator and the counter wheels on the opposite side of said middle counter wheel being readable on the other side of said indicator, and means actuated by the reciprocation of said operating rod to add a unit to each of said indications upon each operation of said operating rod.
18. The combination, with a register, and setting and operating devices therefor, of an indicator separate from said register and comprising a device to indicate the character of the item registered, a second device to compute the number of items registered, and means controlled in unison with said operating device for said register to actuate both of said indicating devices.
19. The combination, with a register, and setting and operating devices therefor, of an indicator separate from said register and comprising a plurality of indicating members each movable relatively to the other, means controlled by said setting and operating devices for said register to select one of said indicating members and move the same into indicating position, said indicator also comprising a series of indicating counter wheels, and means actuated by said operating device for said register to actuate the units counter wheel upon each operation of said operating device.
20. The combination, with a register, an operating device for said register, and means for resetting said register to zero, of an indicator separate from said register and comprising a series of indicating counter wheels, means controlled by the operating device for said register to actuate said indicating device upon each operation of said register, and means actuated by the resetting of said register to reset said counter wheels to zero.
21. The combination, with a register, an operating device for said register, and means for resetting said register to zero, of an indicator separate from said register comprising a resetting shaft, a series of indicating counter wheels mounted on said shaft and arranged to exhibit the same indication on both sides of said indicator, means controlled by the operating device for said register to add a unit to both indications upon each operation of said register, and a connection between said resetting shaft and the resetting mechanism of said register.
22. The combination, with a register, an operating device for said register, and means for resetting said register to zero, of an indicator separate from said register comprising a resetting shaft, a series of indicating counter wheels mounted on said shaft and arranged to exhibit the same indication on both sides of said indicator, means controlled by the operating device for said register to add a unit to both indications upon each operation of said register, means for actuating said resetting shaft, and means for locking said resetting shaft normally against movement.
23. The combination, with a register, an operating device for said register, and means for resetting said register to zero, of an indicator separate from said register comprising a resetting shaft, a series of indicating counter wheels mounted on said shaft and arranged to exhibit the same indication on both sides of said indicator, means controlled by the operating device for said register to add a unit to both indications upon each operation of said register, means for actuating said resetting shaft, means for locking said resetting shaft normally against movement, and means for locking the operating mechanism for said counter wheels against movement while said resetting shaft is being actuated.
24. The combination, with a register, an operating device for said register, and means for resetting said register to zero, of an indicator separate from said register comprising a resetting shaft, a series of indicating counter wheels mounted on said shaft and arranged to exhibit the same indication on both sides of said indicator, means controlled by the operating device for said register to add a unit to both indications upon each operation of said register, a locking plate secured to said resetting shaft, a second locking plate secured to and movable with said operating means for said counter wheels, locking arms rigidly connected one to the other and having parts adapted to be moved into operative engagement with the respective locking plates, said arms being so arranged that when one arm is out of engagement with its locking plate the other arm will be in locking engagement with its plate.
25. The combination, with a register having means to register a plurality of different items, and setting and operating devices for said register, of an indicator separate from said register and comprising a plurality of groups of indicating counters, selective operating mechanism controlled by the setting and operating mechanism for said register to actuate the units counter of that group of counters corresponding to the item which said register is set to register.

26. The combination, with a register having means to register a plurality of different items, and setting and operating devices for said register, of an indicator separate from said register and comprising a plurality of groups of indicating counters arranged to rotate about a common axis, a ratchet wheel connected with the units counter of each group of counters, pawls arranged adjacent to each of said ratchet wheels, means controlled by the operating device for said register for operating said pawls in unison, and means controlled by the setting device for said register to render a part of said pawls inoperative.
27. The combination, with a register having means to register a plurality of different items, and setting and operating devices for said register, of an indicator separate from said register and comprising a shaft, a plurality of groups of indicating counters rotatably mounted on said shaft, and a ratchet wheel connected with the units counter of each of said groups, disks secured to said shaft adjacent to the respective ratchet wheels and each having a recess in the periphery thereof, the recesses of the respective disks being arranged in different positions with relation to said shaft, pawls mounted adjacent to the respective ratchet wheels and extending across said disks, means controlled by the operating device for said register for moving said pawls in unison, and means controlled by the setting device for said register to actuate said disks to move the recess of one of them into a position adjacent to the nose of its pawl, whereby the pawl is permitted to engage the ratchet wheel.
28. The combination, with a register having means to register a plurality of different items, and setting and operating devices for said register, of an indicator separate from said register and comprising a shaft, a plurality of groups of indicating counters rotatably mounted on said shaft, and a ratchet wheel connected with the units counter of each of said groups, disks secured to said shaft adjacent to the respective ratchet wheels and each having a recess in the periphery thereof, the recesses of the respective disks being arranged in different positions with relation to said shaft, pawls mounted adjacent to the respective ratchet wheels and extending across said disks, means controlled by the operating device for said register for moving said pawls in unison, a pinion secured to the end of said shaft, a double faced rack having one face meshing with said pinion, and gearing connecting said setting shaft with the other
- face of said rack, whereby the movement of said setting shaft will shift the positions of the disks on said counter shaft.
29. The combination, with a register having means to register a plurality of different items, and setting and operating devices for said register, of an indicator separate from said register and comprising a plurality of groups of indicating counters arranged to rotate about a common axis, a ratchet wheel connected with the units counter of each of said groups, a pawl-supporting frame mounted on the axis of said counters, pawls carried by said frame to engage the respective ratchet wheels, a pin carried by said frame, a block connected with said operating device for said register and having a cam groove to receive said pin and operate said pawl-supporting frame, and means controlled by the setting device for said register to render a part of said pawls inoperative.
30. The combination, with a register, and setting and operating devices therefor, of an indicator separate from said register and comprising devices to indicate the character of the item registered, other devices to indicate the number of items registered and other devices to indicate the number of items of each class which have been registered, and mechanism for controlling all of said devices from the setting and operating devices of said register.
31. In a device of the character described, a plurality of aligned counter wheels, a ratchet wheel secured to the units counter wheel, a pawl supporting frame mounted on the axis of said counter wheels, a pawl carried by said frame and adapted to engage said ratchet wheel, means for actuating said pawl-supporting frame, a second ratchet wheel mounted on the axis of said counter wheels and disconnected therefrom, a pawl connected with said pawl-supporting frame and adapted to engage the teeth of said second ratchet wheel, a second pawl arranged to be engaged by the teeth of said second ratchet wheel, resilient means to hold said pawls in engagement with said second ratchet wheel, a bell, and a hammer connected with said second pawl and adapted to be actuated by the movement of said second ratchet wheel.

In testimony whereof, we affix our signatures in presence of two witnesses.

WILFRED I. OHMER.
